UNITED STATES PATENT OFFICE

2,537,886

CALENDAR CHRONOMETER

Louis Frank, Fellows, Calif.

Application January 10, 1945, Serial No. 572,130

4 Claims. (Cl. 58—5)

1

My invention relates generally to chronometers such as the conventional forms of clocks and watches, and more particularly to an attachment which may be readily combined with practically all clock and watch movements and operated thereby, for indicating the names of the months, the numbers of the days thereof and the names of the days of the week, thus in effect, providing in the one structure a combined clock and calendar.

One of the principal objects of my invention is, to provide a calendar attachment of the character referred to which is simple in structure, inexpensive of manufacture and which is very compact so that no additional space is required for its installation, inasmuch as practically all forms of clocks and watches now manufactured, have ample space between the dial and movement, for the reception of the calendar mechanism.

A further object of my invention is, to provide simple, practical and convenient means for manually actuating and setting the calendar attachment, so as to compensate for those months having twenty-eight and twenty-nine or thirty days.

My invention also embodies other and more detailed objects and advantages which will become more apparent as the disclosure proceeds.

In the accompanying drawings, wherein similar reference characters designate corresponding parts throughout the several views:

Fig. 1 is a front elevational view of a calendar clock embodying my invention.

Fig. 2 is a vertical section taken through the front portion of the clock just behind the dial and showing the calendar attachment in front elevation.

Fig. 3 is a horizontal section taken on the line 3—3 of Fig. 2.

Fig. 4 is a perspective view of the parts of the calendar attachment in segregated disposition.

Fig. 5 is a detail section taken on the line 5—5 of Fig. 2.

Fig. 6 is a detail section taken on the line 6—6 of Fig. 2.

Fig. 7 is a detail section taken on the line 7—7 of Fig. 2.

Fig. 8 is a vertical section taken on the line 8—8 of Fig. 2.

Fig. 9 is an elevational view taken looking in the direction of the arrow 9 in Fig. 8.

Referring by numerals to the accompanying drawings, which illustrate a preferred embodiment of my invention, 10 designates the housing of a conventional clock (or watch) 11 the hour

2

wheel, 12 the hour hand and 13 the minute hand. A Geneva wheel 14 having eight equally spaced notches, 15 is mounted for rotation on a stud 16 to the side of the hour wheel 11 and projecting from the face of said wheel 14, are four equally spaced pins 17. A pin 18 projects from the face of hour wheel 11 and successively engages in notches 15, thus intermittently rotating the Geneva wheel 14. Formed in the face of Geneva wheel 14 are eight equally spaced recesses 18, which are adapted to successively receive a stud 19, pressed inwardly from a resilient finger 20, that is mounted on stud 16, thus providing a spring detent for said wheel 14.

Sealed in the frame of the clock movement below the hour wheel is a stud 21, on which is mounted a ratchet wheel 22, having thirty-one teeth and formed in the face of this wheel directly opposite said teeth are shallow depressions 23. Appearing on the face of this wheel 22 directly opposite and adjacent the teeth thereof are the numerals, from 1 to 31 inclusive. Projecting from the face of the wheel 22 adjacent the toothed edge thereof is a pin 24. Mounted on stud 21 is an arm 25 and projecting from the end thereof adjacent said teeth are diverging fingers 26 and 27.

Journalled on a stud 28 which is seated in the end of finger 26, is a ratchet wheel 29, having seven teeth, one for each day of the week and the face of said wheel adjacent the teeth thereof, bearing the names or abbreviations of the names of the day of the week.

The teeth of wheel 29 travel in a circular path adjacent the path traveled by the teeth of ratchet wheel 22, and thus the teeth of both wheels 22 and 29 are engaged and intermittently rotated by pins 17 of Geneva wheel 14.

An L-shaped resilient member 30 is secured to stud 21 and one of the arms of said member has an inwardly pressed stud 31, which passes through an aperture 32 in arm 26 and engages successively in recesses 33 that are formed in the face of wheel 29 adjacent the teeth thereof, thus in effect providing a spring detent for said wheel (see Fig. 6).

The other arm of resilient member 30 is pivoted with a stud 34 which passes through an aperture 35 in arm 27 and engages successively in the recesses 23 in wheel 22, thus providing a spring detent for said wheel. (See Fig. 7.)

Journalled on a stud 36 seated in the end of arm 25 opposite the fingers 26 and 27, is a ratchet wheel 37 having twelve teeth, one for each month and the face of bearing the names of the months

and being provided with twelve depressions 38. A flat spring 40, secured at 41 to arm 25 and its other end having a stud 42, which passes through an aperture 43 in said arm and engages in the recesses 23, provides a spring detent for the month wheel 37.

The manually operable means for rotating the wheel 22 to compensate for the different number of days of different months, is illustrated in Figs. 8 and 9 and such means includes an arm 44, journaled on stud 24, and the free end of said arm, carrying a spring pressed detent 45 which engages the teeth of ratchet wheel 22.

The arm is pushed upwardly to move wheel 22 the distance of one tooth, by a spring held plunger 46, operating through the bottom of case or housing 10. (See Fig. 3.) As hour wheel 11 rotates pin 11^a and successively engages in the notches 15 of the Geneva wheel 14 and pins 17 of said Geneva wheel intermittently engage the teeth of the week day wheel 29 and day of the month wheel 22. Two complete revolutions of the hour wheel are required to move week day wheel 29, one tooth, or one-seventh of a complete revolution and the day of the month wheel 22 one tooth, or one thirty-first of a complete revolution, for the reason that the Geneva wheel has eight notches 15 and four pins 17 and thus there is a hiatus or time interval equal to one notch between the engagements of the pins 17 with the teeth of wheels 22 and 29.

Once every revolution of wheel 22, pin 24 engages and rotates wheel 37 the distance of one notch or one twelfth of a revolution. Thus in every thirty-one days the hour wheel 11 makes sixty-two complete revolutions to one revolution of the day of the month wheel 22, seven and three-fourths revolutions of the Geneva wheel, four and three-sevenths of a revolution of the days of the week wheel 29, and one-twelfth of a revolution of the month wheel 37.

Tooth 17 engages one of the teeth of wheel 22 and moves same the required distance before it engages the tooth of wheel 29 and moves same the proper distance (one tooth). In other words, pin 17 moves wheel 29, one seventh of a complete rotation and wheel 22, one thirty-first of a complete rotation.

As seen in Fig. 1, portions of the dial of the clock or watch are cut away to form windows 50 W through which the markings on the wheels 29, 22 and 37 may be readily observed.

Thus it will be seen that I have provided a calendar attachment for clocks, watches and the like, which is simple in structure, inexpensive of manufacture and very effective in performing the functions for which it is intended.

It will be understood that minor changes in the size, form and construction of the various

parts of my improved chronometer attachment may be made and substituted for those herein shown and described without departing from the spirit of my invention, the scope of which is set forth in the appended claims.

I claim as my invention:

1. The combination with a chronometer including a frame and an hour wheel, journaled thereon, which hour wheel has a pin projecting from its face, of a calendar mechanism including a Geneva wheel journaled on said frame, and provided with a series of notches which successively receive the pin of the hour wheel, a bracket mounted on said frame below said hour and Geneva wheels, a week day indicating ratchet wheel journaled on said bracket, the toothed edge of which overlies the edge of the Geneva wheel, a day of the month indicating ratchet wheel, journaled on said bracket, the edge of which day of the month indicating ratchet wheel lies between the overlapping edges of said Geneva wheel and said week day indicating wheel and pins projecting from the face of said Geneva wheel for simultaneously engaging teeth of said day of the week and day of the month wheels, to move same the distance of one tooth each.
2. The combination as set forth in claim 1, with a month indicating ratchet wheel journaled on said bracket and a pin projecting from the face of said day of the month wheel for engaging the teeth of said month indicating wheel and rotating same the distance of one tooth at a time.
3. The combination as set forth in claim 1, with manually operable means mounted on said bracket for imparting step by step movement to said day of the month ratchet wheel.
4. The combination as set forth in claim 1, with detent means mounted on said bracket for holding said week day ratchet wheel and said day of the month wheel at predetermined points in their rotation.

LOUIS FRANK.
